SOIL CORRECTIVES

Albert C. Mohr, Arcadia, Calif., assignor to
Stauffer Chemical Company, a corporation of
California

No Drawing. Application March 5, 1943,
Serial No. 478,131

6 Claims. (Cl. 47-58)

This invention relates to soil additive materials designed to correct and improve the acidity of soil.

It has been recognized in recent years that the acidity or alkalinity of a soil should be altered to improve the workability of the soil, as well as its productivity. To this end, various materials are frequently added to soils. However, these materials are comparatively slow, depending upon action in the soil for liberation of acidifying constituents. This is particularly true in the case of the addition of sulphur or gypsum to the soil. Direct acidification with the sulphuric acid of commerce, while highly desirable, is generally impractical because of corrosion on equipment, and because this material cannot be handled by farm labor cheaply, economically and with any degree of safety. Further, the use of sulphuric acid in a dilute condition involves use of special equipment and, unless handled correctly, may be hazardous to the unskilled. Finally, direct acidification must be done very exactly or serious overdosing may occur.

There are available various industrially exhausted sulphuric acids which are commonly treated to recover the sulphur values therein. I have discovered that a suitably treated acid can serve as a source of sulphur dioxide for subsequent industrial recovery and, at the same time, a coke residue can be formed which can be handled as a solid and which is acceptable as a soil additive. The coke is dry, granular and free-flowing, and can be conveniently handled in ordinary equipment. The coke has such high absorptive properties that it will hold up to half its weight of sulphuric acid and still remain dry. The coke can be produced with the acid present or the acid can be added separately.

To form the soil additive of the present invention, I take a suitable sulphuric acid, one containing sufficient carbon and hydrogen, usually as hydrocarbonaceous material, to form a coke residue on partial desulphurization. This is subject to a thermal de-sulphurization treatment under conditions such that a coke residue containing water soluble sulphuric acid is present in the coke. Such a process is disclosed in my co-pending application Serial No. 474,345 filed February 1, 1943, and in the application of Ross and Wilde Serial No. 453,242 filed August 1, 1942. As is there disclosed, sulphuric acid industrially exhausted in an alkylation process is treated in a suitable furnace under conditions such that the coke is heated to a moderately high temperature, between 500° and 600° F., and a coke residue is

formed. The operation is so conducted that the coke removed from the furnace is dry and free flowing. It can contain between about 10% and about 50% water soluble sulphuric acid.

5 In place of using the process disclosed in the aforesaid applications, one can use any other process wherein a coke residue is formed, care being taken to permit or to ensure the presence in the coke residue of the desired quantity of 10 water soluble sulphuric acid. The use of the process of the applications is, however, particularly desirable because the acid is heated in an atmosphere which does not contain air. This ensures that hydrocarbons present are driven off 15 from the coke and the coke is then nothing but an inert carbon mass which can be added to the soil without harm. Any suitable exhausted acid can be employed, such as a pressure distillate sludge or other acid sludge, so long as the acid 20 content is high enough to permit a dry granular coke to be formed that contains the desired percentage of H_2SO_4 .

After the coke has been produced it is of course removed from the furnace and permitted to cool; 25 if allowed to stand the sulphuric acid will take up water. I have found that by mixing into the coke sufficient of an inert coating material, such as diatomaceous earth fines, clay, talc or the like, to coat the coke particles, the coke mass is cooled 30 sufficiently to permit it to be packaged immediately in airtight containers. It can then be readily handled and shipped. This makes possible the use of ordinary multiple paper bag structures of commerce. With diatomaceous earth fines, about 10% by weight usually suffices.

The present material is quite unique in that if 35 it is attempted to add sulphuric acid to ordinary carriers, for example diatomaceous earth, the maximum quantity of sulphuric acid which can 40 be added without the mass becoming wet and mushy is quite small; by employing the specific coke mentioned, the quantity of sulphuric acid can be materially increased while the product 45 can be packaged in a paper bag for shipment and sale.

If desired, the coke is produced free of any substantial acid content. This is added to the coke after it has cooled, any suitable acid or acid sludge being employed to acidify the coke.

50 The material of this invention is readily applied wherever desired to correct the pH of the soil, the material being scattered and spread and then worked into the soil. The sulphuric acid dissolves out of the coke, while the coke disintegrates in the soil to provide a light, inert diluent im-

proving and lightening the density of the soil so that greater aeration of the soil can be achieved. Because the coke is spread by machine or by hand quite easily and with considerable accuracy, the correct dosage in any selected area can be secured quite readily.

The dosage of the additive will depend on the degree of correction or acidification required. Because of the small, uniform size of the granules (usually all the granules will pass an 8 mesh screen while nearly all will be retained in a 100 mesh screen) the additive is readily spread by hand or by mechanical means. In addition, the small size enables ready control of the dosage. Further, it can be applied close to the base of plants and trunks of trees without injury to these.

I claim:

1. A process for treating soil comprising distributing on the soil and working therein a dry granular coke produced by the partial desulphurization of sulphuric acid sludges derived from petroleum treatment, said coke being substantially free of oil hydrocarbons and containing between about 5% and 50% by weight of water soluble sulphuric acid.

2. A process for treating soil comprising distributing on the soil and working therein a dry granular coke produced by partially thermally desulphurizing a sulphuric acid sludge by heating said sludge derived from petroleum treatment in the substantial absence of air to form a dry granular coke substantially free of oily hydrocarbons and containing water soluble sulphuric acid and removing the coke formed by said thermal desulphurization while it contains a substantial quantity of water soluble sulphuric acid.

3. A process for treating soil comprising distributing on the soil and working therein a dry

5 granular coke produced by thermally desulphurizing a sulphuric acid sludge derived from petroleum treatment by heating said sludge in the substantial absence of air to form a dry granular coke substantially free of oil hydrocarbons, removing the coke formed by said thermal desulphurization and adding sulphuric acid to the coke in an amount up to about 50% of the weight of the coke.

10 4. A process for treating soil comprising distributing on the soil and working therein a dry granular coke produced by the partial desulphurization of alkylation acid sludge, said coke being substantially free of oil hydrocarbons and containing between about 5% and 50% by weight of water soluble sulphuric acid.

15 5. A process for treating soil comprising distributing on the soil and working therein a dry granular coke produced by partially thermally desulphurizing an alkylation sulphuric acid sludge by heating said sludge in the substantial absence of air to form a dry granular coke substantially free of oily hydrocarbons and containing water soluble sulphuric acid and removing the coke formed by said thermal desulphurization while it contains a substantial quantity of water soluble sulphuric acid.

20 6. A process for treating soil comprising distributing on the soil and working therein a dry granular coke produced by thermally desulphurizing an alkylation sulphuric acid sludge by heating said sludge in the substantial absence of air to form a dry granular coke substantially free of oil hydrocarbons, removing the coke formed by 25 said thermal desulphurization and adding sulphuric acid to the coke in an amount up to about 50% of the weight of the coke.
